UNITED STATES PATENT OFFICE.

HARRY ROBERT NORTHOVER, OF WINNIPEG, MANITOBA, CANADA.

FLASH-ABSORBER ATTACHMENT FOR MACHINE-GUNS.

1,242,843.

Specification of Letters Patent.

Patented Oct. 9, 1917.

Application filed September 7, 1916. Serial No. 118,807.

To all whom it may concern:

Be it known that I, HARRY ROBERT NORTHOVER, gunsmith, subject of the King of Great Britain, residing at 217 Graham avenue, Winnipeg, Manitoba, in the Dominion of Canada, have invented certain new and useful Improvements in Flash-Absorber Attachments for Machine-Guns, of which the following is a specification.

This invention has reference to devices (technically known as "flash-absorbers") which are designed to be attached to the barrel of a machine-gun for the purpose of obscuring or screening the flash of discharge, and thereby rendering it difficult or impossible for an enemy to detect or ascertain the position of a gun by observing the locality in which the flash appears.

The said invention consists in an improved flash-absorbing device, as herein-after described; which, when attached to the muzzle of a machine-gun barrel, not only functions effectively as a means for screening or concealing the flash or flame of discharge, but also serves to substantially muffle or deaden the report, while the construction of the said attachment is such that, when applied to or used in connection with a gas-operated automatic fire-arm (such as a Colt automatic gun) it does not detrimentally affect the working of the said gun or the rate of fire. On the contrary, the attachment, by setting up or creating a certain back pressure in the barrel of the gun, has the effect of speeding up the working of the automatic mechanism.

A machine-gun attachment constructed in accordance with this invention comprises or embodies three intercommunicating chambers, one of which is in direct communication with, and is practically an extension of, the muzzle end of a gun-barrel and is so constructed or fitted internally that it permits of the passage of the bullets therethrough but deflects or diverts the gases issuing from the said barrel downwardly into a second or intermediate and much larger chamber which serves as an expansion chamber and wherein the combustion of the unburnt gases occurs or is completed. The products of such combustion then pass into a third or outer chamber which is formed with a system of gas-vents where-through the said products are expelled into the atmosphere, and also with a system of air-inlet holes that provide for the admis-

sion or circulation of air into or through the appliance; the said gas-vents and air-inlet holes in this last chamber being so disposed as to reduce to an absolute minimum the possibility of the flash, flame or glare created by the firing of the gun, or by the burning of the powder gases within the attachment, being externally visible at any distance from the front of the gun when the latter is in action.

Figure 1 of the accompanying drawing represents a side elevation of a gun attachment constructed in accordance with the said invention.

Fig. 2 is a top plan of the same.

Fig. 3 is a longitudinal vertical section, while

Figs. 4 and 5 are, respectively, a transverse vertical section on line X, Fig. 3, and front end elevations of the device.

The same letters of reference indicate corresponding parts in the several figures of the drawing.

In the construction represented in the said figures, *a* is the gas-deflecting chamber, *b* is the second or intermediate chamber, and *c* is the third or outer chamber; the whole of these chambers or compartments being in communication with one another, as herein-after described.

The gas-deflecting chamber *a*, consists of a cylinder or tube of suitable length and diameter whose axis (when the attachment is fixed to the muzzle of the gun) is in alignment with the bore of the barrel. The underside of the middle portion of this cylinder is formed with a series of relatively large gaps or apertures at *a*¹, *a*², *a*³, all leading into the expansion chamber *b* while its cylindrical front part *a*⁴ has no such gap, and is adapted to serve as a spark-arrester. The interior of this cylinder is divided or partitioned off into a succession of compartments by means of deflector plates *a*⁵, *a*⁶, *a*⁷, which are fixed at a forwardly-sloping inclination (for instance, at an angle of 45 degrees relative to the axis) and are each pierced with a central hole *a*⁸ that coincides or registers with the muzzle of the barrel and with a hole in the forward end *a*⁹ of the chamber to provide for the passage of the bullets through the said chamber. One of these inclined deflector plates is disposed immediately in front of each of the bottom apertures of the cylinder as clearly shown in Fig. 3, so that said plates serve to direct

the powder gases downwardly through the said apertures into the expansion chamber *b* while the forward or spark-arrester part is also fitted with one or more similar plates 5 *a*¹⁰ whose function is to intercept and arrest sparks or incandescent particles that may pass the plates *a*⁵, *a*⁶, *a*⁹ and so prevent the escape of such sparks or particles into the atmosphere through the hole *a*⁸ at the forward end of the chamber.

10 Preferably the central holes or openings in the inclined plates are successively decreased in diameter from rear to front of the chamber so that while the plate nearest the muzzle has the largest gas-clearance and offers the minimum resistance to the forward travel of the gases, the next plate, having a smaller clearance, offers a correspondingly increased resistance, and so on; 15 the result being that an approximately equal proportion of gas is passed through each of the apertures into the expansion chamber. For the same purpose, the apertures themselves may also be of different relative areas, 20 in which case, the aperture nearest the muzzle may be the largest, while the others diminish in size as they approach the front end of the deflecting chamber.

25 Additional and smaller holes or piercings 30 *a*¹¹ may also be made in the side and bottom walls of the deflecting chamber to facilitate the passage of gases into the expansion chamber.

35 The expansion chamber *b* consists of another cylinder, of the same length as the deflecting chamber but much larger in diameter. It is closed at both ends and entirely envelops the parts of the said deflecting chamber wherein the gas-outlets or apertures 40 *a*¹, *a*², *a*³ are formed, but it is disposed in eccentric relation to the deflecting chamber, so that when the attachment is fixed to a gun, practically the whole of the body of the expansion cylinder is located below the axis 45 of the barrel, where it cannot interfere with the sighting. The interior of the said cylinder is clear or unobstructed so as to permit the free or unimpeded expansion of the gases therein, while its bottom walls are 50 pierced with a number of holes or perforations *b*¹ wherethrough the combustion products resulting from the burning of the gases (whether in the gun-barrel or within the said cylinder) pass freely into the third 55 compartment *c* of the attachment.

60 This third chamber *c* preferably has a semi-cylindrical shape and is fixed in concentric relation to the bottom half of the expansion chamber, where it incloses or 65 covers the whole of the perforations *b*¹ in the latter and thus externally screens or hides the flash or glare arising from the burning of the gases inside the other chambers, while the vents or outlets for the final escape of the combustion products into the

atmosphere are formed at *c*¹ in the rear end of this screening chamber, and also (if necessary) at *c*² along the flat or horizontally-positioned webs or flanges *c*³ whereby the upper edges of the said screening chamber 70 are connected to the opposite side walls of the expansion cylinder; this disposition of the vents providing a free escape of the said gases while obviating any possibility of even reflected light from the internal 75 burning of the gases being visible from the front of the gun.

To provide for a back air-current into and through the attachment for assisting or insuring the complete combustion of 80 gases within its interior, the front end *c*⁴ of the screening chamber is pierced with a system of minute holes *c*⁵ whose aggregate area is sufficient to admit all the air that is required but which individually are so small 85 that internal flash cannot be seen therethrough.

For fixing or anchoring the attachment to the muzzle of a gun barrel, the rear end of the deflecting chamber may be combined 90 with a split sleeve or adapter clip *d* which is adapted to be passed over the said barrel and contracted thereon by a clamping screw *d*¹ or the like. Further, to prevent longitudinal displacement, this clip may be provided with grip or pinion screws *d*² that bind onto the barrel; or it may be furnished with one or more pins or screws, whose point or points may be engaged with depressions or recesses in the barrel when the 95 attachment is in position, while the said sleeve may also carry a hooked or forked anchoring extension piece, the hook or fork of which may, by a partial rotary movement of the appliance relative to the barrel, 100 be engaged over or behind the fore-sight of the gun. Any other suitable construction of adapter or connecting device may be used instead of that above described.

Having now particularly described and ascertained the nature of my said invention, and in what manner the same is to be performed, I declare that what I claim is:—

1. A combined flash-absorber and silencer for guns, comprising a tubular gas-deflecting chamber adapted to fit at its rear end upon a gun barrel in axial alinement therewith and having the under side of its middle portion formed with a longitudinal series of gaps; a series of deflector plates, one for 110 each gap, fixed within said chamber and extending forwardly and downwardly from the upper side of the chamber directly to the forward edges of the gaps, said plates being provided with central openings alining axially with one another and with the bore of the gun barrel to permit the bullet to travel therethrough; and a cylindrical 115 expansion chamber, into the body of which the gases are deflected directly downward 120

125

130

135

through said gaps by said plates, eccentrically encircling the deflecting chamber and so arranged with respect thereto that substantially its entire body portion is located 5 below the axis of said deflecting chamber, said expansion chamber being closed at opposite ends.

2. A combined flash-absorber and silencer for guns, comprising a tubular gas-deflecting chamber adapted to fit at its rear end upon a gun barrel in axial alinement therewith and having the underside of its middle portion formed with a longitudinal series of gaps; a series of forwardly-inclined deflector plates fixed within said chamber, one 10 at the front edge of each gap, said plates being provided with central openings alining axially with one another and with the bore of the gun barrel to permit the bullet to travel therethrough; a cylindrical expansion chamber encircling the deflecting chamber and into which the gases are deflected 15 through said gaps by said plates, said expansion chamber being closed at opposite ends and having its bottom wall formed with 20 perforations through which said gases pass; and a chamber inclosing the perforated portion of the bottom wall of said expansion chamber.

3. A combined flash-absorber and silencer for guns, comprising a tubular gas-deflecting chamber adapted to fit at its rear end upon a gun barrel in axial alinement therewith and having the underside of its middle 25 portion formed with a longitudinal series of gaps; a series of forwardly-inclined deflector plates fixed within said chamber, one at the front edge of each gap, said plates being provided with central openings alining 30 axially with one another and with the bore of the gun barrel to permit the bullet to travel therethrough; a cylindrical expansion chamber encircling the deflecting chamber and into which the gases are deflected 35 through said gaps by said plates, said expansion chamber being closed at opposite ends and having its bottom wall formed with perforations through which said gases pass; and a chamber inclosing the perforated portion of the bottom wall of said expansion chamber and having its front wall provided with air inlets and its rear wall with gas outlets.

4. A combined flash-absorber and silencer for guns, comprising a tubular gas-deflecting chamber adapted to fit at its rear end upon a gun barrel in axial alinement there-

with and having the under side of its middle portion formed with a longitudinal series of gaps; a series of deflector plates, one for 60 each gap, fixed within said chamber and extending forwardly and downwardly from the upper side of the chamber directly to the forward edges of the gaps, said plates being provided with central openings alining axially with one another and with the bore of the gun barrel to permit the bullet to travel therethrough, the portion of the chamber in advance of the foremost gap being closed 65 at its front end to constitute a spark-arrester and being formed with a central opening alining with the bore of said barrel; a forwardly and downwardly inclined deflector plate disposed within said spark-arrester and extending from top to bottom thereof to 70 arrest and intercept sparks or incandescent particles which may have passed the first-named deflector plates, the spark-arresting deflector plate having a central opening which alines with the openings in said first-named plates; and a cylindrical expansion chamber, into the body of which the gases are deflected directly downward through 75 said gaps by said first-named plates, eccentrically encircling the deflecting chamber 80 and so arranged with respect thereto that substantially its entire body portion is located below the axis of said deflecting chamber, said expansion chamber being closed at 85 opposite ends.

5. A combined flash-absorber and silencer for guns, comprising a tubular gas-deflecting chamber adapted to fit at its rear end upon a gun barrel in axial alinement therewith and having the under side of its middle 90 portion formed with a longitudinal series of gaps; a cylindrical expansion chamber encircling the deflecting chamber and into which the gases are deflected from the latter by way of said gaps, said expansion chamber 95 being closed at opposite ends and having its bottom wall formed with perforations through which said gases pass; and a chamber inclosing the perforated portion of the bottom wall of said expansion chamber and 100 having its front wall provided with minute air inlets and its rear wall with gas outlets.

In testimony whereof I have hereunto set my hand in presence of two subscribing witnesses.
